UNITED STATES PATENT OFFICE.

ALEX DOW, OF DETROIT, MICHIGAN.

ELECTRIC FURNACE.

1,161,634.

Specification of Letters Patent. Patented Nov. 23, 1915.

Application filed May 29, 1914. Serial No. 841,740.

To all whom it may concern:

Be it known that I, ALEX Dow, a citizen of the United States of America, residing at Detroit, in the county of Wayne and State 5 of Michigan, have invented certain new and useful Improvements in Electric Furnaces, of which the following is a specification, reference being had therein to the accompanying drawings.

- 10 The invention relates to electric furnaces, and particularly to that class in which a resistor is formed by a body of granular material, such as coke or other form of carbon. With such constructions it is usual to place 15 the granular body within a casing or holder of refractory and electrically insulating material, the terminals being arranged at opposite ends of this casing and the heat being generated by the comparatively high resistance of the granular material. The work is 20 arranged to receive the heat by radiation from the exposed surface of the resistor body, and the temperature may be regulated by variation in the pressure upon said body. 25 A serious difficulty which has been experienced with furnaces of this type is that of controlling the path of the current through the resistor body. It is desirable to use a bed of some considerable thickness in order 30 to obtain a more uniform resistance and to compensate for loss by surface oxidation. This, however, renders it difficult to maintain uniform electrical resistance through the cross section of the bed and there is a 35 constant tendency toward the lowering of the resistance at the bottom of the bed and the increasing of the resistance at the work surface thereof. This is due partly to the fact that carbon has a negative temperature 40 coefficient and the lowering of the temperature of the exposed surface, due to radiation and absorption by the work will increase the resistance thereof. This will result in the deflection of the current into a 45 lower portion of the resistor bed, with the objectionable effect of increasing the heat developed adjacent to the refractory lining, while diminishing the heat generation at the surface where it is most effective for distribution to the work. Thus the efficiency of 50 the apparatus is lessened and the intensified heat in the lower strata of the resistor has a detrimental effect upon the refractory case.

With the present invention I overcome 55 this objection by the provision of means for deflecting the current into a path adjacent

to the work-distributing surface of the resistor. Preferably electro-magnetic means is employed for this purpose, and where, as is usual, alternating current is employed the 60 magnetism may be produced inductively thereby.

Various constructions may be employed for carrying out my invention, but, as shown,—Figure 1 is a longitudinal section 65 through a furnace to which my improvement is applied; Fig. 2 is a cross section thereof; Fig. 3 is a plan view of the frame of magnetic bars; Fig. 4 is a cross section showing the electrically insulated mechanical connection between the bars; and Fig. 5 is a diagram showing a modified construction.

A is a casing formed of refractory material, within which is arranged a bed B of 70 the granular resistor material, with a work chamber C above the same having an opening D for the insertion of the work therein. E are the terminals through which the current is supplied to the resistor arranged at 75 opposite ends of the casing. With the construction as thus far described, when work, such as a metal bar E', is introduced into the heating chamber it will be heated partly by direct radiation from the surface of the 80 resistor bed and partly by reflection from the top of the chamber C. The rapid absorption of heat by the work will, however, result in lowering the temperature of the 85 surface of the bed, which will increase the electrical resistance thereof, and furthermore, where the work is a magnetic metal, such as iron, it will act inductively upon the current passing through the resistor, tending to deflect the same downward. This 90 will have the objectionable results previously described. To utilize this effect, I have provided a series of bars F of magnetic material, such as iron, which extend transversely of the path of current through 95 the resistor and across the bottom of the casing A and also upward upon opposite sides thereof to approximately the level of the upper surface of the resistor bed. The bars F are supported in this position by a connection with longitudinally-extending bars 100 G, but to avoid short circuiting, this connection is electrically insulated. Thus, as shown in Fig. 4, the bolt H which clamps each bar F to the bar G is provided with an 105 insulating sleeve I and insulator washers J and J' to prevent electrical connection with

said bars, while an insulating strip K interposed between the bars prevents direct electrical connection therebetween.

With the construction as described, when 5 current is applied to the furnace it will pass principally through that portion of the resistor adjacent to the working surface of the resistor, thereby intensifying the heat at this point and diminishing the heating 10 effect adjacent to the refractory lining. This action is due to the fact that the metallic bars described are arranged each with its respective magnetic axis so related to the line of flow of electric current as to permit 15 the induction of maximum magnetism and thereby cause the greatest repulsion of current.

Where desired, the effect may be still further intensified by forming one or more 20 convolutions of the conductor L around the cross section of the bars F before the current enters the resistor body, as shown in Fig. 5.

What I claim as my invention is:—

25 1. In an electric furnace, the combination with a refractory casing, of a resistor bed therein having an exposed surface, terminals passing through opposite walls of the casing through which current is supplied to 30 the resistor bed, and electro-magnetic means for deflecting the path of the current through said bed toward the exposed surface thereof.

2. In an electric furnace, the combination 35 with a refractory casing having a work chamber, of a resistor bed within the casing adjacent to said chamber, and electro-magnetic means for deflecting the path of the current through said bed toward the work chamber.

3. In an electric furnace, the combination 45 of a refractory casing and a resistor bed therein, of electro-magnetic means for deflecting the path of the current through said resistor from the surface adjacent to said casing toward the exposed surface thereof.

4. In an electric furnace, the combination 50 with a resistor, of terminals engaging opposite points of the same through which current is supplied to the resistor, and a series of magnetic bars arranged transversely of the path of the current through said bed for deflecting the current toward a 55 certain surface of the resistor.

5. In an electric furnace, the combination

with a refractory case, of a resistor bed therein, and a series of magnetic bars arranged transversely of said bed across the bottom thereof for deflecting the current 60 toward the upper surface.

6. In an electric furnace, the combination with a refractory casing, of a resistor bed therein, and a series of magnetic bars extending transversely across the bottom of 65 said casing and upward along the sides thereof, for the purpose described.

7. In an electric furnace, the combination with a refractory case and a resistor bed therein, of a frame comprising a series of 70 transversely-extending magnetic bars and longitudinally-extending bars connected to and insulated therefrom, said frame being arranged with the magnetic bars extending transverse to the path of the current 75 through said resistor bed to deflect the same to the upper surface thereof.

8. In an electric furnace, the combination with a refractory case, of a resistor bed therein, and a frame formed of parallel-U- 80 shaped magnetic bars and connecting cross bars insulated therefrom, said frame being arranged with said parallel bars extending transverse to the path of the current through said resistor and extending across 85 the bottom and upward along the sides of said case.

9. In an electric furnace, the combination with a resistor, of a metallic body arranged adjacent to said resistor, producing deflection of the current passing through the resistor through the induction by the resistor of a magnetic field in said body.

10. In an electric furnace, the combination with a refractory casing and a resistor 95 bed therein, having an exposed work surface, of a metallic body exterior to the casing, producing a deflection of the current in the resistor bed toward the work surface thereof through the induction by said current of a magnetic field in said body.

11. In an electric furnace, the combination with a resistor, of means utilizing the resistor as an inductor to produce a magnetic field deflecting the current in the resistor.

In testimony whereof I affix my signature in presence of two witnesses.

ALEX DOW.
